UNITED STATES PATENT OFFICE.

WILLIAM H. SAART, OF ATTLEBORO, MASSACHUSETTS, ASSIGNOR TO THE
JAMES E. BLAKE COMPANY, OF SAME PLACE.

DESIGN FOR A BACK FOR BRUSHES OR SIMILAR ARTICLES.

SPECIFICATION forming part of Design No. 34,642, dated June 11, 1901.

Application filed May 21, 1901. Serial No. 61,307. Term of patent 3½ years.

To all whom it may concern:

Be it known that I, WILLIAM H. SAART, a citizen of the United States, residing at Attleboro, in the county of Bristol and State of Massachusetts, have invented and produced a new and original Design for the Back of a Brush or Similar Article, of which the following is a specification, reference being had to the accompanying drawings, forming part thereof.

Figure 1 is a plan view of the back, showing my new design. Fig. 2 is a cross-section of the back on the line X X of Fig. 1, and Fig. 3 is a transverse section through the handle on the line Y Y of Fig. 1.

As shown in the drawings, the leading or material feature of my design consists of the raised ornamentation representing the conventional form of two oppositely-disposed dragons with inwardly-curved wings at the head of the back. The flamboyant tails of the dragons extend along the two side mar-

gins and join the scrolled tails of two oppositely-disposed raised conventional representations of dolphins, from the mouths of which 25 scrolled bands extend over the handle. The 30 ornamentations inclose a convex panel on which a nude female figure in relief surmounts curved lines resembling the surf of the sea. Flowing raised bands resembling seaweed 35 surround a mask on the end of the handle and extend upward on the handle.

Having thus described my invention, what I claim as new, and desire to secure by Letters Patent, is—

The design for a back of a brush or similar article, as herein shown and described.

In testimony whereof I have signed my name to this specification in the presence of two subscribing witnesses.

WILLIAM H. SAART.
